UNITED STATES PATENT OFFICE

2,391,782

POLICE WEAPON

Robert L. Hutchison, Roma, Tex.

Application February 11, 1944, Serial No. 521,997

5 Claims. (Cl. 273—84)

This invention relates to a weapon primarily for use in law enforcement.

It is particularly aimed to provide a structure adapted for use somewhat like a "blackjack" or "billy" and it aims to provide such a structure which is generally flexible and will have a more telling and effective blow-producing function, with less effort than heretofore and with less chance of gashing or bruising the scalp of the prisoner.

It is further particularly aimed to provide a structure which may be made from leather or equivalent flexible material providing a pouch containing a mass of shot and also providing a hand hold or gripping opening.

In addition, it is aimed to provide a structure which is not bulky so that it may be carried by the officer concealed to better advantage than heretofore, in fact, in any pocket practically unnoticeable, a construction which will always be in a position for use, one which will be comfortable to the officer, especially when sitting, and a structure which may be more effectively grasped by the officer and held to better advantage against danger of its being wrested from him.

The more specific objects and advantages will become apparent from a consideration of the description following taken in connection with accompanying drawing illustrating an operative embodiment.

In said drawing—

Figure 1 is a view in elevation of the improved weapon;

Figure 2 is a central longitudinal section taken on the line 2—2 of Figure 1;

Figure 3 is a plan view of the main blank of the weapon in unfolded or flat condition;

Figure 4 is a cross-sectional view taken on the line 4—4 of Figure 1; and

Figure 5 is an elevational view of a spacing and reinforcing frame or strip which may be used.

Referring specifically to the drawing wherein like reference characters designate like or similar parts, a blank is provided in flat form as shown in Figure 3, and it is preferably of leather although it may be made of any suitable material. This blank provides connected side walls 10 which are foldable upon each other at their connections as at 11. After folding of the walls 10 toward each other, a spacing frame or strip 12 is disposed between them at the margins of the walls 10 and is stitched thereto as at 13. It will be noted that the walls 10 have registering openings at 14 and that a strip or frame 15 is disposed between walls 10 and surrounds such open-

ings and is secured in place by stitching as at 16. The openings 14 provide a hand-hold so that the weapon may be effectively grasped. It will also be noted that at the end opposite to the hand-hold a pouch or sac is formed which is filled with a loose mass of metallic particles or other weighted articles, preferably shot, as at 17.

The strips or frames 12 and 15 are preferably of leather like the walls 10 and the stitching at 13 and 16 is accomplished with a heavy waxed thread. While the shot may be disposed directly in the pouch as shown, the same may however, be held in a buckskin or other sac so that in the event of ripping of the stitching, the balls 17 will 15 still be retained in place.

It is to be understood that the structure may be of any desired size and shape and that the portion provided with the hand-hold may be wider than the pocket or shot-carrying portion, 20 or vice versa.

The strips at 12 and 15 add stiffness at the edges of the structure and provide smooth edges.

The weapon is adapted for use primarily substantially like a "blackjack" or "billy" in subduing prisoners and it provides a relatively flat, wide, flexible construction which will deal a more telling and effective blow with less effort than heretofore and at the same time with less danger of injury by gashing and bruising the scalp or face of the person being subdued. A firm hand-hold can be had on the weapon with the fingers and free movement of the knuckles had even when wearing gloves.

Various changes may be resorted to provided 35 they fall within the spirit and scope of the invention.

I claim as my invention:

1. A weapon of the class described comprising superposed walls providing a pocket, a mass of discrete weight particles in said pocket, and the walls having a hand opening therethrough.

2. A weapon of the class described comprising superposed walls providing a pocket, a mass of discrete weight particles in said pocket, the walls having a hand opening therethrough, a spacing strip secured between the walls marginally thereof, and a spacing strip secured to the walls between the same and marginally of the hand-hold.

3. A weapon of the class described having connected walls, means securing the walls together marginally, said walls providing a pocket, a mass of discrete weight elements in said pockets, and the walls having a hand opening therethrough.

4. A weapon of the class described having connected leather walls, means securing the walls

together marginally, said walls providing a pocket, a mass of discrete balls in said pocket, the walls having a hand opening therethrough.

5. A weapon of the class described having connected leather walls, means securing the walls together marginally, said walls providing a pocket, a mass of discrete balls in said pocket, the

walls having a hand opening therethrough, a strip stitched in place between the walls and marginally thereof, and a strip stitched in place between the walls and to the same marginally of the hand-hold.

ROBERT L. HUTCHISON.
